LOCK

John W. Fitz Gerald, Milwaukee, Wis., assignor
to Briggs and Stratton Corporation, Milwau-
kee, Wis., a corporation of Delaware

Application August 19, 1929, Serial No. 386,956

5 Claims. (Cl. 70—91)

This invention relates to certain new and useful improvements in locks and refers more particularly to the type adapted for use with automotive vehicle door handles.

5. It is an object of this invention to provide a lock of the character described which is so constructed that persons familiar with its construction may remove the cylinder.

Another object of this invention is to simplify 10 the construction of locks of this character and to reduce the manufacturing costs thereof.

Another object of this invention resides in the provision of a lock of the character described in which cooperating stop means are carried by 15 the mounting member and the lock cylinder, one of which is yieldable to permit withdrawal of the lock cylinder when in a predetermined relative position with respect to the mounting member.

Another object of this invention resides in the 20 provision of a lock of the character described in which cooperating means carried by the mounting member and the lock cylinder normally secure the lock cylinder in the mounting member, said means being disengageable when the lock cylinder is in a predetermined position relative 25 to the mounting member, and the provision of means for preventing accidental disengagement of the cooperating means when the cylinder is in said predetermined position.

30. And a more specific object of this invention resides in the provision of an abutment carried by the mounting member and an annular groove formed in a lock cylinder carried part normally in engagement with the abutment and having a portion, which when aligned with the mounting 35 member carried abutment, permits withdrawal of the lock cylinder upon the application of outward stress thereto.

With the above and other objects in view which 40 will appear as the description proceeds, my invention resides in the novel construction, combination and arrangement of parts substantially as hereinafter described and more particularly defined by the appended claims, it being understood 45 that such changes in the precise embodiment of the herein disclosed invention may be made as come within the scope of the claims.

In the accompanying drawing, I have illustrated 50 one complete example of the physical embodiment of my invention constructed according to the best mode I have so far devised for the practical application of the principles thereof, and in which:

55. Figure 1 is a view partly in section and partly in elevation of a vehicle door handle equipped with my improved lock structure.

Figure 2 is a view similar to Figure 1 and illustrating the cylinder turned to a medial position to permit withdrawal of the cylinder.

Figure 3 is a cross-sectional view taken through Figure 2 on the plane line 3—3; and

Figure 4 is a fragmentary perspective view of the inner end of the cylinder carried pin or extension.

5. Referring now more particularly to the accompanying drawing in which like numerals designate like parts throughout the several views, the numeral 5 represents a conventional vehicle door handle having a shank 6 and a tubular shank 10 extension 7 secured thereto in any desired manner as by being cast into the shank 6 during the die-casting of the handle. A longitudinal bore 8 is formed in the handle member in axial alignment with the shank 6 to receive a casing 9 preferably formed of steel or other similar hard material and in which a lock cylinder 10 of conventional construction is received.

The casing 9 is substantially closed at its inner end, from which a pair of tongues 11 extend to be received in grooves 12 formed in the adjacent end of the shank extension 7 to secure the casing 9 against rotation in the bore 8. An aperture in the inner end of the casing 13 permits a pin 14 extended from the cylinder to pass 25 therethrough and be received in the tubular shank extension 7.

The cylinder 10, being of conventional construction, is provided with a plurality of locking tumblers, not shown, normally projected into 30 one of a pair of longitudinal slots 15 in the casing 9 to secure the cylinder and the pin 14 against rotation, the tumblers being retractable within the periphery of the cylinder upon the insertion of a proper key 16 to free the cylinder 35 for rotation as is customary. Rotation of the cylinder is limited, in the present instance, to approximately 180 degrees by the engagement of a stop, comprising a lug 17 extended from the outer end of the casing 9, with either of a pair 40 of abutments 18 formed in the outer enlarged end 19 of the cylinder.

The rotary movement of the cylinder and the pin 14 is translated into a reciprocating movement of a locking pin 20 slidably mounted in a 45 transverse recess 21 formed in the outermost end of the shank extension 7, by the engagement of an eccentric pin 22, extended from the adjacent end of the pin 14, with a transverse slot 23 formed in the locking pin. When the cylinder is in its locked position the locking pin 20 has one end projected beyond the periphery of the shank extension 7 and into a recess formed in a door carried stationary element, not shown, to prevent rotation of the handle assembly, and 55 when the cylinder is turned to its unlocked position the pin 20 is withdrawn from the recess to permit unrestricted turning of the handle. The movement of the handle is imparted to the door latching mechanism not shown, by means 60

of a squared lug 24 extended from the closed outer end of the shank extension 1.

To releasably secure the cylinder in the handle, a fixed stop comprising a transverse pin 25 is fixed in the shank extension so that its inner medial portion forms a cord to the inner periphery of the extension, to be engageable in an annular groove 26 formed in the cylinder extension or pin 14. One side 27 of the groove 26 is 10 preferably straight and in a plane at substantial right angles to the axis of the pin to provide a sharp abutment engageable with the cross pin 25 to normally prevent outward movement of the pin and cylinder.

15 However, to permit the cylinder to be inserted and removed when necessary, the outermost portion of the pin 14, or that portion extending between the groove 26 and its outermost end, has a portion thereof cut away to form a flat surface 28, which when aligned with the cross pin 25, clears the same and permits insertion and withdrawal of the cylinder. The groove and the flatted surface thus forms substantially a bayonet slot, in which the flatted surface provides 20 the outlet. The position of the flatted side 28 with respect to the cross pin 25 is such as to align with the cross pin when the cylinder is turned to an approximately medial position, thus necessitating the use of a key in withdrawing the cylinder and thereby preventing its unauthorized removal.

To preclude the possibility of the cylinder being accidentally withdrawn, and to necessitate a proper knowledge of the construction of the 35 lock before the cylinder can be withdrawn, means are provided which normally prevent withdrawal of the cylinder, even though the flatted side 28 of the pin 14 is aligned with the cross pin 25. This means consists of a ball or the like 29 mounted in a recess 30 formed in the flatted portion of the pin 14 adjacent the groove 26 and normally yieldably urged to project beyond the flatted surface 28 by an expansive spring 31, disengagement of the ball from the recess being 40 prevented by the inwardly swedged peripheral edge 32 of the recess. The projecting portion of the ball 29 thus substantially forms a continuation of the side 27 of the annular groove 26 and prevents accidental disengagement of the 45 groove and the cross pin 25. The application of sufficient outward stress, however, readily disengages the groove and the cross pin by forcing the ball into its recess.

50 From the foregoing description taken in connection with the accompanying drawing it will be readily apparent to those skilled in the art to which an invention of the character described appertains that I have provided a novel means for retaining a lock cylinder assembled with its 55 mounting member which is extremely simple in design, inexpensive to manufacture, and requires only the turning of the cylinder to a medial position and the application of outward stress on the key to effect withdrawal.

60 65 What I claim as my invention is:

1. In a lock device of the character described, a mounting member having a bore opening to its front end, a lock cylinder inserted into the mounting member bore from its front end and movable therein in the performance of its locking functions, and cooperating means carried by the mounting member and the lock cylinder for normally retaining the lock cylinder assembled with

the mounting member, one of said means being yieldably maintained in operative position and being movable to inactive position to enable withdrawal of the cylinder from the mounting member upon movement of the cylinder to a predetermined position relative to the mounting member and the application of an outward stress on the cylinder to disengage the cylinder. 5

2. In a lock device of the character described, a mounting member, a lock cylinder mounted therein, an abutment carried by the mounting member, an abutment carried by the lock cylinder and cooperating with the mounting member carried abutment to normally prevent withdrawal of the lock cylinder from the mounting member, and one 10 of said abutments having a portion thereof yieldable to permit withdrawal of the lock cylinder when in a predetermined position relative to the mounting member and subjected to an axial 15 stress. 20

3. A lock device, comprising a mounting member, a lock cylinder movable therein in the performance of its locking functions, an abutment carried by the mounting member, an abutment carried by the lock cylinder and normally engageable with said mounting member carried abutment to prevent withdrawal of the lock cylinder means whereby said abutments may be disengaged from each other upon movement of the lock cylinder to a predetermined position relative to the 30 mounting member, and yieldable means normally preventing withdrawal of the lock cylinder when in said predetermined position, said last means yielding upon the application of an axial stress on the lock cylinder when in said predetermined 35 position to free the cylinder for withdrawal.

4. A lock device comprising, a mounting member, a lock cylinder member movable therein in the performance of its normal locking functions, an abutment carried by the mounting member and engageable in a groove formed in the lock cylinder member to secure the lock cylinder member in the mounting member without interfering with the locking functions of the lock cylinder member, said groove having an outlet whereby the abutment may be disengaged therefrom when the members are in a predetermined relative position, and yieldable means normally blocking the outlet to prevent accidental withdrawal of the lock cylinder member, said yieldable means being movable to inoperative position by the application of outward stress to withdraw the lock cylinder member. 45 50

5. In a lock device of the character described, a mounting member, a lock cylinder movable therein and having an extension, an abutment carried by the mounting member and normally engageable in a groove formed in the lock cylinder extension to releasably secure the lock cylinder in the mounting member, the lock cylinder extension having a portion thereof cut away to provide an entrance to the groove through which the mounting member carried abutment is movable to permit withdrawal of the lock cylinder when in a predetermined position relative to the mounting member, and yieldable means carried by the lock cylinder extension and engageable with the mounting member abutment when the lock cylinder is moved to said predetermined position, whereby the withdrawal of the cylinder necessitates the application of unusual stress on the cylinder. 60 65 70

JOHN W. FITZ GERALD.

CERTIFICATE OF CORRECTION.

Patent No. 2,000,279.

May 7, 1935.

JOHN W. FITZ GERALD.

It is hereby certified that error appears in the printed specification of the above numbered patent requiring correction as follows: Page 2, second column, line 8, claim 1, strike out the words "to disengage the cylinder"; and that the said Letters Patent should be read with this correction therein that the same may conform to the record of the case in the Patent Office.

Signed and sealed this 18th day of June, A. D. 1935.

Leslie Frazer
